UNITED STATES PATENT OFFICE.

LOUIS V. MARTEL AND PHILIP METHOT, OF MANCHESTER, NEW HAMPSHIRE, AS
SIGNORS OF ONE-THIRD TO OSCAR F. MOREAU, OF MANCHESTER, NEW HAM-
SHIRE.

WASHING MACHINE.

Application filed May 20, 1922. Serial No. 562,399.

To all whom it may concern:

Be it known that we, LOUIS V. MARTEL and PHILIP METHOT, citizens of the United States, residing at Manchester, in the county 5 of Hillsborough and State of New Hampshire, have invented new and useful Improvements in Washing Machines, of which the following is a specification.

As in our United States Letters-Patent 10 granted February 22, 1921, and No. 1,369,686, our present invention has reference to a clothes washing apparatus.

Our object is to simplify and improve the construction disclosed in our said patent.

Other objects will also appear as the nature of the invention is better understood, reference being had to the drawings which accompany and form part of this specification.

20 In the drawings:—

Figure 1 is a side elevation of the improvement.

Figure 2 is a top plan view thereof.

Figure 3 is a vertical transverse sectional view approximately on the line 3—3 of Figure 1.

Figure 4 is a horizontal sectional view approximately on the line 4—4 of Figure 1.

Figure 5 is a sectional view on the line

30 5—5 of Figure 2.

Figure 6 is a sectional view on the line 6—6 of Figure 3.

As in the construction disclosed by our mentioned Patent No. 1,369,686, we dispense 35 with the employment of dashers, pounders, and other devices which are liable to inflict injury to clothes in the washing thereof, and in lieu thereof subject the clothes to a continuous whirling action of water delivered 40 under pressure thereagainst, the said water being continuously used during the washing operation and therefore effecting a saving of the water.

In our referred to patent, we made use of 45 four rotary pumps which forcibly delivered streams of water through apertured compartments at varying elevations. This manner of delivering saponaceous water is also resorted to in our present construction, but 50 in lieu of forming the casing or tub with integral apertured compartments, we employ a perforated member in the nature of a clothes receiving basket through which the fluid outlets from a single pump are ar- 55 ranged at varying heights. Also in our

present construction, we aim to materially simplify and cheapen the drive means for the pump as well as to likewise simplify and improve the controlling means for the motor which operates the pump. 60

Referring now to the drawings in detail, the numeral 1 designates a preferably metal casing that constitutes the body of the improvement. The casing is preferably square or rectangular in plan and has its upper edge reinforced by metal members 2, and the corners of the casing having attached thereto legs 3 which are preferably constructed of angle irons and which depend a suitable distance below the bottom of the 70 casing. The legs preferably have their lower ends enlarged or otherwise formed with feet 4 that afford a firm bearing in the floor or other support for the device. Preferably there is connected with each of the legs, 75 at the bottom thereof, a bearing for a roller, and above the rollers the legs support a flanged tray or false bottom 5. On this tray there is secured a motor 6. The motor is preferably electrically driven and is provided with suitable controlling means. On the motor shaft there is keyed or otherwise secured a worm gear 7 which is in mesh with a worm gear 8 on a cross shaft 9 which is journaled in suitable bearings supported 80 upon the tray. These bearings also support a boxing that provides a case for a portion of a shaft 9 and for the worm gears 7 and 8. In the boxing 50 there is arranged on the shaft 9 a slidable friction clutch element 51. 85

The element 51 has a hub or sleeve portion 53 that receives a spline 44 on the shaft 9. The hub is also provided with an annular groove in which there is received the bifurcated or forked end of a lever 55 which is pivotally supported, as at 56, upon the top of the boxing 50. Journaled in suitable bearings in the side of the boxing 50 is a shaft 57. This shaft, at a portion thereof arranged in the boxing, has a cam head 58. The shaft 57 has its end provided with an angle lever 57' which is vertically directed and which has thereon a lug. The lever is received in a slotted guide 58' that is provided with two spaced notches in either 95 of which the lug on the lever is to be received, as when the clutch element 51 is moved in either a forward or rearward direction.

Secured at one end of the boxing 50 there 100

is a shaft 59 which is in longitudinal alignment with the shaft 9. On the shaft 59 there is secured a female friction clutch element 60 arranged opposite the male clutch element 51.

The shaft 59 is the propelling shaft for the blades of a rotary water pump 17.

By reference to the drawings it will be noted that the bottom 19 of the body 1 is inclined inwardly and downwardly from the lower edges of the body. The casing of the pump 17 has its intake pipe 18 connected directly to the lowermost point of the bottom of the body 1. To the pump casing there is secured an outlet pipe 20 that is provided with four branches 21 respectively, each directed to the corners at the bottom of the casing. These branch pipes are connected to the outlet pipe by a coupling 27. Threadedly engaging or, if desired, providing extensions for the branches 21 there are vertically disposed pipes 22 that enter the casing at the corners thereof. Each of these pipes is of a different length, one of the pipes terminating very close to the bottom of the casing, another a suitable distance above the bottom, another at a still further distance above the bottom and the last pipe 22 terminates near the top of the casing. All of the pipes 22 have angle nozzle ends 24, directed toward the center of the casing 1. It is to be understood that saponaceous water is poured into the open top of the casing, so that the same will pass through the intake 18 into the pump casing and when the pump is operated such water will be ejected through the outlet pipe 20 and the branches therefor and be forcibly directed at different angles through the nozzles 24.

The clothes receiving receptacle or basket is in the nature of a cylindrical member and is broadly indicated by the numeral 25. The basket 25 has its upper edge provided with a flange 26, the said flange corresponding to the interior shape of the casing 1, and consequently is in contact with all of the four sides thereof. The nozzles 24 pass through openings in the sides of the basket, and the said basket has its lower wall provided with depending plates 27 arranged angularly with respect to each other and having their lower edges cut at an inclination to rest on the inclined portions of the bottom of the casing 1. The plates 27 thus hold the bottom of the basket elevated with respect to the bottom of the casing, and the forcibly injected sprays of water finding an outlet through the reticulated basket will be brought into contact with the plates. The plates thus serve as obstructing elements for the whirling stream of water, and direct the same to the intake 18 of the pump 65 so that such water will be delivered into the

pump casing at a steady and not in a whirling stream.

The coupling 27 between the outlet pipe 20 and the branch pipes 21 is preferably constructed of two sections which may be bolted or otherwise secured together. The lower tubular section is provided with an angle branch 28 to which is coupled a hose 20' that provides an outlet for the water after the washing process. The branch 28 is, however, normally closed by a valve 31, the inner end of the said branch being in the nature of a seat for the said valve. The valve is in the nature of a flat member, round in plan, and having an ear 32 at its upper end which is seated in a suitable pocket provided in the coupling 27. The ear is provided with a stem 33 that passes through one side of the coupling, the stem being in the nature of a shaft, and the end thereof not passing through the coupling being received in a bearing depression provided therefor. The projecting end of the stem or shaft has a handle 34. The wall of the coupling opposite the valve seat may be notched, as at 36 and the valve 31 is limited when moved to a position to open the branch 28 by contact with the shoulder provided by the said notch. The upper section of the coupling 27 necessarily includes four branches, and to the respective branches the pipes 21 are connected. The branches 37 of the coupling are rounded upwardly from the straight lower portion of the said coupling. The upper and inner wall of the coupling at the juncture of the branches 37 therewith is substantially V-shaped in cross section and is centrally provided with a threaded opening. In this opening there is screwed a bolt 39 that has its lower end pointed, as at 40. The pointed end 40 of the bolt defines four right angular substantially V-shaped faces. The bolt 39 is designed to direct water through the respective ports 37 of the coupling 27 so that substantially an equal amount of water will be directed through all of the pipes 21 from the pump.

It is believed that the foregoing description, when taken in connection with the accompanying drawings will fully set forth the construction, operation and advantages of the improvement. It will be apparent to those skilled in the art to which this invention relates that clothes placed in the basket and subjected to the forcibly injected angle streams of water that pass through the nozzles will contact with the clothes at different angles and in this manner remove the dirt from the clothes. Other than the sprays of water delivered against the clothes, there is no pounding action and it is never necessary for the operator to place his hands in the basket except for the insertion and removal of the clothes. Thus

articles of the finest fabric may be readily cleaned without danger of injury thereto.

The clutch operated lever is disposed conveniently with respect to the hand of the operator. The motor controlled means is arranged conveniently for actuation by the foot of the operator. After the washing process the water is let out of the device in a manner as previously described.

10 Having described the invention, we claim:—

1. In a clothes washing machine, a casing having a downwardly inclined bottom, a fluid pump having an intake pipe connected with the lowest part of the bottom, an outlet pipe for the pump, branches secured thereto and directed through different parts of the bottom adjacent to the sides of the casing, the outlet pipes in the 15 casing being of different lengths and having nozzles secured to the ends thereof, a removable reticulated clothes receiving basket arranged in the casing and having its bottom provided with depending plates 20 which rest on the bottom of the casing, and means for operating the pump.
2. In a clothes washing machine, a casing having a substantially funnel-shaped bottom, a rotary pump having an inlet connected to the lowest part of the bottom of 30 the casing, an outlet for the pump having branches directed toward and passing through the bottom adjacent to the corners of the casing and terminating at different elevations in the casing, a removable 35 foraminous basket in the casing having a flanged upper edge to contact with the walls of the casing, and means on the bottom thereof resting on the bottom of the casing providing baffles for the water from the 40 pump to direct the same in a steady stream into the intake of the pump, nozzles between the outlet branches of the pump and the basket, a motor drive for the pump, clutch means between the shaft of the motor and 45 the shaft of the pump, and operating means for said clutch means.

In testimony whereof we affix our signatures.

LOUIS V. MARTEL.
PHILIP METHOT.
